UNITED STATES PATENT OFFICE.

CHARLES A. LINDSTROM, OF CHICAGO, ILLINOIS.

DESIGN FOR AN AUTOMOBILE ELECTRIC-MOTOR CASE.

SPECIFICATION forming part of Design No. 32,326, dated March 6, 1900.

Application filed January 26, 1900. Serial No. 2,921. Term of patent 7 years.

To all whom it may concern:

Be it known that I, CHARLES A. LINDSTROM, a citizen of the United States, and a resident of Chicago, Cook county, Illinois, have invented and produced a certain new and original Design for Electric-Motor Cases for Automobiles, of which the following is a full, clear, and exact specification, reference being had to the accompanying drawings, in which—

10 Figure 1 is a side view of my design for cases for the electric motors of automobiles, and Fig. 2 is an end view thereof.

As shown in the drawings, the principal and leading feature of my design consists in 15 a motor-case closed at both ends, and comprising, first, a cylindrical-shaped field-ring A, having a convexed exterior circumference, and provided with a slightly raised and flattened attaching-surface *a* at one side and at 20 a point almost diametrically opposite but above the surface *a* with a projecting sus-

pending-lug *b*; second, a closed cylindrical end section B of less diameter having an end bearing boss *f*, flattened on top, and, third, an opposite cylindrical and tapered end section ²⁵ C, which is of a greater diameter and length than section B, but less than the field-ring, and also has an end bearing boss flattened on top, all substantially as shown.

Having thus described my invention, what ³⁰ I claim as new, and desire to secure by Letters Patent, is—

The design for an automobile electric-motor case, as herein shown and described.

In testimony whereof I have signed my ³⁵ name to this specification in the presence of two subscribing witnesses.

CHARLES A. LINDSTROM.
